UNITED STATES PATENT OFFICE.

WALTER H. UNDERWOOD, OF NEW YORK, N. Y.

LOOM.

1,109,090.

Specification of Letters Patent. Patented Sept. 1, 1914.

Application filed October 28, 1912. Serial No. 728,303.

To all whom it may concern:

Be it known that I, WALTER H. UNDERWOOD, a citizen of the United States, and resident of New York, county of New York, 5 and State of New York, have invented certain new and useful Improvements in Looms, of which the following is a specification.

This invention relates to looms and more particularly to improvements whereby the 10 looms of the type in common use are adapted to weave the fabric described and claimed in my Patent No. 1,012,031, issued December 19, 1911.

15 The yarn described in my above mentioned patent is found to be more or less "sticky" when it is attempted to weave the same on the ordinary loom, because of the nature of the fibers, they having microscopical saw-like edges which cause the contacting yarns to stick together. This stickiness prevents the weft or filler from being beaten up closely to the woven fabric and also, owing to the fact that some of the 20 25 yarns are weaker or tauter than others, causes breakage of the yarns, rendering a stoppage of the loom necessary.

It is the object of the present invention to overcome these difficulties in the weaving 30 of metallic yarns so that a uniform and closely woven fabric may be produced. I accomplish these objects by having each of the warp threads passed through a small tube which extends rearwardly from a point 35 close to the woven fabric to a point rearward of the reed which beats the weft or filler into position. A single yarn passes through each of these tubes and as the tubes are of just sufficient size to permit the yarns 40 to pass therethrough, the surface fibers of the yarns will be smoothed out. When desired, more than one warp thread may be passed through each tube, as for example, two warp threads are passed through each 45 tube in making what is known as the "basket" weave. The weft or filler, in being beaten up engages the smooth outer surface of the tubes and is therefore readily beaten into position.

50 A further object is to provide means for having a comparatively wide-open shed to receive the weft, and this is accomplished by having the ends of the tubes close to the woven fabric so that when the weft is beaten

up the ends of the tubes are separated, thereby opening the shed.

It will be obvious to those skilled in the art that the invention may be embodied in various forms of mechanism, some of which are illustrated in the accompanying drawings, and therefore I do not wish to be limited to these particular mechanisms, but claim all mechanisms for this purpose which come within the scope of the appended claims.

In the drawings—Figure 1 is a more or less diagrammatic view of certain portions of a loom of ordinary construction, embodying one form of the invention, the view being a longitudinal section; Fig. 2 is a plan view of the parts shown in Fig. 1; Fig. 3 is a perspective view of one form of tube; Fig. 4 is a perspective view of another form of tube; Fig. 5 is a diagrammatic view of another form of mechanism for holding the tubes in position; Fig. 6 is a diagrammatic view showing the manner in which the shed is opened by the weft or filler; Fig. 7 is a diagrammatic view of a third form of mechanism for holding the tubes in position; Fig. 8 is a perspective view of the forward end of a tube which may be used in the mechanism shown in Fig. 7.

Referring to the drawings and more particularly to Figs. 1 and 2, 10 indicates one of the side frames of a loom, 11 and 12 the harness frames, 13 the lay and 14 the reeds for beating the weft or filler into position. The warp threads 15 and 16 pass through eyes of the heddles 17, these threads being 85 separated by means of the heddles to form the shed which extends from the point 18, this point being the end of the woven fabric. The warp threads 15 and 16 pass through the tubes 19 and 20, respectively, 90 these tubes having their forward ends arranged as closely as practicable to a point 18 and extending rearwardly to a point beyond the rearmost position of the reeds 14. The tubes may be circular in cross section 100 as shown in Fig. 3, or oval or they may be rectangular, as shown in Fig. 4, and each tube is provided at its rearward end with an eye 21 to which may be attached the device for holding the tube in position so that it 105 will not be carried along with the warp threads and woven into the fabric.

As shown in Figs. 1 and 2, the device for

holding each of the tubes in position comprises an upright rod 22 having its ends pivotally connected to links 23 and 24, these links being of the same length and being pivoted at their forward ends to rods 25 and 26 extending transversely of the loom and mounted in adjustable brackets 27 and 28, respectively. The brackets 27 are secured to supports 29 which are provided with slots 30 to receive the bolts 31 for securing the brackets thereto. The brackets 28 are similarly connected with a supporting member 32 and it will be obvious that the slots will permit the brackets to be adjusted longitudinally of the loom for the purpose of adjusting the tubes.

In Fig. 1 the reed 14 is shown in its rear-most position and when the parts are in this position the shuttle is passed through the triangular space between the reeds and the tubes to place a weft or filler thread therein. The lay 13 is then moved forwardly and beats the weft up to the point 18. As will be readily observed, the weft thread, in being beaten up to the point 18, engages the smooth outer surface of the tubes 19 and 20 and since these tubes are very close together at their forward ends, the weft will separate the ends, as shown in Fig. 6, and open the shed so that the reeds can beat the weft up close to the thread previously laid. After the weft has been beaten into position the harness frames 11 and 12 are shifted in the usual manner, the frame 11 moving downwardly from the position shown in Fig. 1 to the level of the frame 12 and the latter frame moving upwardly from the position shown in Fig. 1 to the level of the frame 11. The operation of passing the shuttle through the shed and beating up the weft is then repeated.

As the harness frames move they carry the warp threads with them and also the tubes. From Fig. 1 it will be obvious that as the warp threads are shifted the eyes 21 on the tubes will be caused to move in circular arcs approximately about the point 18 so that the tubes will be maintained in practically the same position relative to that point.

In the plan view shown in Fig. 2, the woven fabric is drawn on an exaggerated scale in order to more clearly illustrate the same.

In order to weave a fabric having closely arranged warp threads the sides of the tubes may be cut away for a short distance from their forward ends as shown at 34 in Fig. 3, this cutting of the tubes enabling the packing of the filler more closely against the sides of the warp threads.

In cases where it is desirable to open the shed to an unusual amount, rectangular tubes, as shown in Fig. 4, may be employed. These tubes are arranged with their longer sides arranged vertically and are provided at

their ends with plugs or eye-lets 35 through which the warp threads pass. It will be obvious that the shed will be open to a considerable extent by the weft when it passes the forward ends of the rectangular tubes.

In Fig. 5 I have shown another device for holding the tubes, this device consisting of an arc shaped arm 36 secured to the tube and passing through a suitable guide 37 secured to the frame of the machine in any suitable manner. It will be obvious that in this construction the tube will not move longitudinally of the warp thread as the latter is shifted from the full line position to the dotted line position shown in Fig. 5.

In Fig. 7 I have shown another device for holding the tubes in position, this device consisting of a flexible wire or cord 38 which is secured to the eye 21 of the tube and passes rearwardly alongside of the warp thread and through the eye in the heddle and is secured to a rod 39 which extends transversely of the loom at a point preferably directly above the beam or point where the warp threads divide in passing to the heddles to form the shed. It will be obvious that the wire 38 will hold the tube against forward movement and to overcome any tendency for the tube to be drawn rearwardly by the reed, the forward end of the tube may be split as shown in Fig. 8 and the ends slightly crimped so that the tube will engage the warp thread at this point with sufficient friction to prevent its rearward movement.

The effective length of the tube will ordinarily amount to only two or three inches from the forward end thereof, but since it is necessary to prevent the tubes from catching the reed during the beat they are made long enough to extend to a point rearward of the reed.

Where it is the purpose to merely prevent the weft threads from sticking during the beat the tubes may be made of flexible material such as woven silk or other smooth fabric, or a fine, closely wound metal wire spring in the form of a tube may be used.

In some instances, in order to prevent the tubes from being woven into the fabric it may be necessary to withdraw the tubes slightly after the weft has been beaten up and it will be obvious that this may be readily accomplished with the devices which I have shown for holding the tubes. For example, in the device shown in Fig. 1, if the links 23 are shorter than the distance between the eyes 21 on the tubes and the point 18, the tubes will be drawn rearwardly to a slight extent when the harness frames are shifted.

Having thus described my invention, what I claim is:

1. In a loom, a reed for beating the weft into position and tubular members adapted to receive the warp threads and extending

forwardly and rearwardly of the limits of movement of the reed.

2. In a loom, a reed for beating the weft into position, tubular members, adapted to receive the warp threads, and having their forward ends arranged close to the woven fabric and their rear ends arranged rearward of the rearmost position of said reed, for the purpose described.

10 3. In a loom, a reed for beating the weft into position, tubular members adapted to receive the warp threads, and having their forward ends arranged close to the woven fabric whereby the weft will open the shed as it passes the forward ends of the tubular members.

4. In a loom, means for beating the weft thread into position, shedding mechanism, and means whereby the shed is additionally 20 opened at the fabric to permit the weft to be laid close to the fabric.

5. In a loom, means for beating the weft into position, means for shifting the positions of the warp threads, and means independent of said last mentioned means for 25 opening the shed at the fabric to permit the weft to be laid close to the fabric.

6. In a loom, tubular members adapted to receive the warp threads, and having their 30 forward ends arranged close to the woven fabric, and means for holding said tubular members in position on the warp threads, for the purpose described.

7. In a loom, tubular members adapted to 35 receive the warp threads, and having their

forward ends arranged close to the woven fabric, and means for holding said tubular members in position, said tubular members having their side portions cut away at their forward ends.

8. In a loom, rectangular tubular members adapted to receive the warp threads, and having their forward ends arranged close to the woven fabric, and shedding mechanism for moving said members in parallel planes, for the purpose described.

9. In a loom, tubular members of oblong rectangular cross section adapted to receive the warp threads and having their longer sides arranged vertically, said tubular members having eyelets in their ends through 50 which the warp threads pass, for the purpose described.

10. In a loom, reeds for beating the weft into position, tubular members adapted to receive the warp threads and having their forward ends arranged close to the woven fabric and their rearward ends arranged rearward of the rearmost position of said reeds, and means connected with said tubular 60 members rearwardly of said reeds and adapted to hold the tubular members in position.

In testimony whereof I affix my signature in presence of two witnesses.

WALTER H. UNDERWOOD.
